UNITED STATES PATENT OFFICE.

HENRY S. PRENTISS, OF NEW YORK, N. Y.

CLOCK-MOVEMENT AND THE LIKE.

SPECIFICATION forming part of Letters Patent No. 416,804, dated December 10, 1889.

Application filed April 3, 1889, Serial No. 305,863. (No model.)

To all whom it may concern:

Be it known that I, HENRY S. PRENTISS, a citizen of the United States, and a resident of New York, in the county and State of New York, have invented a new and useful Improvement in Clock-Movements and the Like, of which the following is a specification.

My invention has reference to improvements in mechanical motors, and especially to such as are adapted for use in cases where uniformity of motion and a constant impulse are essential—such, for instance, as motors for operating the feed-rolls of magnesium lights or in clock-movements.

Primarily the object of my invention is to obtain by the use of purely mechanical means a practically uniform impulse, especially in spring-motors, where otherwise the impulse varies with the variation of tension in the springs. My improvement is therefore especially applicable to time-pieces, which in consequence thereof can be supplied with very powerful mainsprings and will run accurately for a long period of time without recurring winding, the effect on the pendulum or other timing devices being constant regardless of the tension of the mainsprings.

With the above object in view I combine with a motor an equalizing-spring which is connected with and continually actuates a movable member of the motor, said spring being wound up at predetermined intervals by the motor, all of which is more fully pointed out in the following specification and claims and illustrated in the accompanying drawings, in which—

Figure 1 represents a vertical section in the plane x x , Fig. 2, of a spring-motor embodying my invention. Fig. 2 is a vertical section thereof in the plane y y , Fig. 1. Fig. 3 is a section in the plane z z , Fig. 2, showing the equalizing device. Figs. 4 and 5 are detail views. Fig. 6 is a section in the same plane as Fig. 1, but showing the parts in different relative positions. Fig. 7 is a sectional elevation showing my improvement applied to a clock-movement. Fig. 8 is a vertical section in the plane x' x' , Fig. 7.

Similar letters and figures indicate corresponding parts.

In the drawings, referring at present to

Figs. 1, 2, and 3, the letter A designates the frame of the motor, and B is the mainspring, arranged as usual and provided with the usual means for winding. The first or great wheel C of the motor is connected by a train of gear-wheels with a pinion D, mounted loosely upon a post a , which is rigidly secured in the frame A.

E is a spindle or shaft arranged in line 60 with the post a , which shaft can turn freely in suitable bearings, one of which may be directly in the end of the post and the other in the frame. This spindle or shaft I shall hereinafter term the "main shaft" E, and it 65 is the member to which a uniform impulse is imparted and from which power is transmitted directly or indirectly to any mechanism or device—such, for instance, as to the feed-rolls of a magnesium light or to the 70 pendulum or regulator of a time-piece.

To the pinion D is connected so as to turn with the same an arm F, projecting radially therefrom, and provided at or near its ends with laterally-projecting stops 1 and 2, which 75 are arranged to be successively engaged by a stop 3, located at the end of an arm G, affixed to a rock-shaft b .

H is the equalizing-spring, which at the outset is placed under a definite tension, and 80 which I have shown in the form of a spiral spring, having its inner end attached to the main shaft E and its outer end secured to a post on the winding-arm F. On the main shaft is an eccentric 4, which engages with a bifurcated arm I, projecting from the rock-shaft b , the vibrations of said arm, due to the rotation of the main shaft, being transmitted to the stop-bearing arm G.

Referring to Figs. 1 and 2, the stop 1 on the 90 winding-arm F is engaged by the stop 3 of arm G, and consequently is prevented from turning in the direction of arrow 10, in which direction the force of the mainspring B would normally impel it. In the meantime the equalizing-spring, being under tension, turns the main shaft in the direction of arrow 10. When the eccentric 4 draws the arm I downward, or in the direction of arrow 11, Fig. 1, the stop 1 is released from stop 3, and the mainspring 95 is free to act. The winding-arm F, under the impulse of the mainspring, is rotated in the 100

direction of arrow 10 until the stop 2 is engaged by the stop 3, (see Fig. 4,) which, as here shown, is one-half a rotation, and the equalizing-spring is wound up to correspond. 5 When the main shaft has turned sufficiently to cause the eccentric 4 to raise the arm, the stop 2 is released from stop 3 and the winding-arm completes the revolution. On inspection of Figs. 1 and 3 it will be noticed 10 that stop 1 is farther removed from the center of the arm F than stop 2, so that when the arm G is in its highest position the upper edge of stop 3 will engage with the lower edge of stop 1, and when in its lowest position the 15 lower edge of stop 3 will engage the upper edge of stop 2.

The equalizing-spring H is best made in the form of a spiral spring, and in practice I make use of a very long light spring, which at the 20 outset is placed under a definite tension. This tension is sustained by the periodical rewinding to which the spring is subjected.

Instead of winding the spring periodically through half a turn, as illustrated, the winding-arm and the stops could be arranged to coil the spring periodically through one-quarter of a turn or less; but I have found that when a long hair-spring is used no appreciable increase of tension follows the winding of 30 the spring through a half-turn. It will be noticed that the main shaft E rotates in the same direction as the spring is wound, and that it turns through half a revolution before the rewinding of the spring takes place. Consequently the impulse on the shaft is constant at all times.

From the foregoing description it will be readily understood that the general function of the equalizing-spring is to transmit 40 constantly to the main shaft a definite impulse regardless of the existing tension of the main-spring or other source of power, the said equalizing-spring being always wound to a definite extent and always under the same tension.

The form of motor just described is especially adapted for magnesium lights, where a constant impulse is required for continuously feeding the ribbon along, the velocity with 50 which the rolls are turned being determined by any suitable timing device. One form of timing device I have illustrated in Figs. 7 and 8 of the drawings—viz., an escapement and pendulum, as ordinarily used in clocks—and 55 I will now describe the arrangement of my improvement in time-pieces.

I will not at present enter into the construction of the clock-movement here shown, as my equalizing device can be applied to 60 any well-known movement.

In Figs. 7 and 8, E' is the arbor of the scape-wheel J, which arbor corresponds to the main shaft of Figs. 1 and 2. The inner end of the equalizing-spring H is secured to said arbor 65 as before, and the pinion D, carrying the arm F, is connected with the train of wheels constituting the clock-movement, and conse-

quently is ultimately in connection with the center wheel K on the center arbor N. The scape-wheel J is engaged by an anchor L, connected with a pendulum M, as usual. The action of the motor is the same as before. While the stop 3 engages either of the stops 12 the train of wheels is held out of action; but on release of either stop 1 or stop 2 it is 75 free to move and to actuate the hands m and h of the clock. As here shown, the clock-movement is released at every half-revolution of the scape-wheel J, which is so geared that the hands are moved twice each minute 80 through a space corresponding to one-half a minute on the dial at each release of the motor. In the case of clocks embodying a weight-movement the equalizing-spring counteracts any irregularities in the construction of the 85 gears constituting the movement and any variation in the friction thereof. The use of such powerful mainsprings as my invention will permit of would ordinarily involve the use of a crank-arm or its equivalent for winding the said springs. This I propose to avoid 90 by placing the winding arbor or arbors outside of the spring or springs.

In the example shown in Figs. 7 and 8 of the drawings I employ a common winding-arbor O for both mainsprings B' B', which is connected by trains of gears c d e with the first or great wheels C' C' and by a third train f g with the center arbor, said trains at the same time forming also a portion of the clock-train, and the trains c d e reducing the power required at the winding-arbor. The pinion c of train c d e is made fast to the winding-arbor O, while the gear-wheel f of train f g is loose thereon and carries a detent i, engaging 105 a ratchet-wheel j, fast on the arbor O, so that in winding up the springs this wheel f will not rotate. The winding-arbor may be similarly placed and connected when only one mainspring B' is used in the clock-movement, 110 and it is evident that three or more mainsprings could be geared together in the same manner.

What I claim as new, and desire to secure by Letters Patent, is—

1. In a clock-movement, an equalizing-spring for the governing member and a main-spring for actuating the train, normally held out of action and released at determinate intervals to rewind the equalizing-spring and 120 to actuate the movement, substantially as described.

2. In a clock-movement, a mainspring for actuating the train, normally held out of action, an equalizing-spring for the governing member, adapted to be coiled by said main-spring, and a device actuated by the uncoiling of the equalizing-spring to release the mainspring, said mainspring on its release recoiling the equalizing-spring and actuating 130 the train, substantially as described.

3. In a clock-movement, a stop for holding the mainspring out of action, an equalizing-spring for the governing member incorpo-

- rated in said movement, and a device for releasing the mainspring to coil the equalizing-spring and to actuate the train, substantially as described.
- 5 4. In a clock-movement, a timing device, an equalizing-spring for the timing device controlled thereby, a mainspring for recoiling the equalizing-spring at determinate intervals and for actuating the train during such periods of recoiling, a stop for the mainspring, and a device actuated through the uncoiling of the equalizing-spring to release the mainspring from the action of the stop, substantially as described.
- 15 5. In a clock-movement, a mainspring for actuating the train, normally held out of action, an equalizing-spring for the governing member, adapted to be coiled by said mainspring through the intermediate train, and a device actuated by the uncoiling of the equalizing-spring to release the mainspring, said mainspring, when released, recoiling the equalizing-spring and actuating the movement during such period of recoiling, substantially as described.
- 25 6. In a clock-movement, an equalizing mechanism incorporated in the train or hand-actuating mechanism and controlling the mainspring, said mainspring recoiling the spring of the equalizing mechanism and actuating the said train during the period of recoiling the said spring, substantially as described.
- 35 7. The combination of a mainspring, an equalizing-spring, a winding-arm arranged to be actuated through an intermediate train by the mainspring to coil the equalizing-spring, and suitable stopping and releasing devices, substantially as described.
- 40 8. The combination of a mainspring, an equalizing-spring, a winding-arm arranged to be actuated through an intermediate train by the mainspring to coil the equalizing-spring, an escapement for controlling the uncoiling of the equalizing-spring, and suitable stopping and releasing devices, substantially as described.
- 45 9. The combination of a mainspring, a revoluble shaft, a train of gear-wheels between the shaft and the mainspring, all constituting a motor, a winding device carried by one of the gear-wheels of the train, an equalizing-spring having one end attached to the shaft and the other to the winding device, a regulator or governing member, a stop for holding the mainspring out of action, and a releasing device actuated at determinate intervals, substantially as described.
- 55 10. In a mechanical motor, the combination of the mainspring, a main shaft, a winding-arm, a spring having its inner end attached to the main shaft and its outer end to the winding-arm, a tripping mechanism actuated
- by the main shaft, and a gear-connection between the mainspring and the winding-arm, 65 substantially as described.
11. The combination, with the mainspring and the main shaft, of a winding-arm having two stops, a spring attached to the main shaft and to the winding-arm, a stop for successively engaging the stops on the winding-arm, a cam or eccentric on the main shaft for actuating the latter stop, and a connection between the mainspring and the winding-arm for actuating the latter when released from the stop, substantially as described.
12. An equalizing mechanism for spring-motors, consisting of a revoluble shaft, a winding-arm arranged to turn about a center in line with the shaft and provided with two stops, an equalizing-spring having one end attached to the revoluble shaft and one to the winding-arm, an arm provided with a stop adapted to engage with the stops of the winding-arm, a cam on the revoluble shaft, 85 and an arm engaged by the said cam and connected with the stop-bearing arm, substantially as described.
13. In a mechanical motor, the combination of a mainspring, a winding-arbor, and gears connecting the winding-arbor with the spring-gear, said gears forming a part of the train of the motor, substantially as described.
14. In a mechanical motor, the combination of two or more mainsprings, a common winding-arbor, gears connecting the winding-arbor to the spring-gears, and a train of gears connecting the winding-arbor to the center arbor, said gears forming a part of the train of the motor, substantially as described.
15. In an equalizing mechanism for spring-motors, a revoluble shaft, an escapement-wheel mounted on said shaft, a winding device, a spring having one end attached to the shaft and the other to the winding device, 105 and a gear connected with the motor and actuating the winding device, all said parts being arranged about one and the same center line or axis, substantially as described.
16. The combination, with the frame A, of a post a, secured in said frame, a shaft E, arranged in line with the post and having a bearing therein, a winding device F, mounted on the post, a spring H, connected with the shaft and the winding device, a stop, and a 115 cam 4, engaging said stop, substantially as described.
- In testimony that I claim the foregoing as my invention I have signed my name, in presence of two witnesses, this 29th day of March, 1889.

HENRY S. PRENTISS.
